UNITED STATES PATENT OFFICE.

HOMER G. KELLOGG, OF DETROIT, MICHIGAN, ASSIGNOR TO MOTOR PRODUCTS CORPORATION (1923), OF DETROIT, MICHIGAN, A CORPORATION OF NEW YORK.

METHOD OF FORMING HINGES.

Application filed November 13, 1922. Serial No. 600,639.

The invention relates to the manufacture of hinges of that type commonly known as piano hinges. The main idea embodied in the invention is the forming of a hinge by one continuous operation, increasing the rate of production and decreasing the cost of manufacture. Another feature is the severing of an advancing flat metallic strip into a pair of longitudinal sections and the subsequent fashioning of the sections into hinge members. In addition to these features, the invention has further features as more fully hereinafter set forth.

In the drawings:

Figures 1 and 2 are respectively a side elevation and a plan view of a machine for carrying out my method;

Figures 3, 4 and 5 are plan views showing different stages in the development of the hinge;

Figures 6, 8, 11, 12, 14, 16, 17, 18 and 19 are cross sections on the lines, 6—6, 8—8, 11—11, 12—12, 14—14, 16—16, 17—17, 18—18 and 19—19 respectively of Figure 1;

Figures 7, 9, 10, 13 and 15 are cross sections on the lines 7—7, 9—9, 10—10, 13—13 and 15—15 respectively of Figure 2.

Figure 20 is a perspective view of a portion of the formed hinge.

In general, the hinge of the type commonly known as a piano hinge is formed from a flat metallic strip of indeterminate length which is continuously advanced, and during its advancement is severed into two longitudinal sections having alternate interengaging tongues extending longitudinally thereof and subsequently has its sections fashioned to form hinge members. More specifically, the tongues of the sections are fashioned around a wire to form barrels, this wire being continuously advanced with the strip.

Figures 1 and 2 disclose a machine for carrying out my method in which 1 represents a pair of shearing rolls, and 2, 3, 4, 5, 6, 7 and 8 successive pairs of driven forming rolls, these forming rolls and shearing rolls all being driven in timed relation to each other through the series of intermeshing gears 9 extending longitudinally of the machine. Stationary dies and also idler forming rolls are provided intermediate different pairs of the driven forming rolls for carrying out certain steps in my method.

A flat metallic strip 10 shown in Figure 3 and coiled to form a reel rotatably mounted in advance of the machine is continuously advanced through the machine and the first step in the forming of the hinge comprises the shearing of the strip by the shearing rolls 1 into a pair of longitudinal sections having the bodies 11 and the alternate interengaging tongues 12 extending longitudinally thereof as shown in Figure 4.

The sections then pass through the first pair of forming rolls 2 which crimp the tongues 12 intermediate their ends and deflect the outer ends of the tongues of one section upwardly above the plane of the body of the other section, the sections after this step appearing as shown in Figures 5 and 6.

After the tongues of the sections have been crimped, the sections are then moved laterally toward each other to bring the tongues of one section into overlapping relation with the body of the other section, this being accomplished by passing the sections through a die 13 intermediate the pairs of forming rolls 2 and 3 and having a rearwardly tapering guideway for receiving the sections and moving the same laterally toward each other, thereby bringing the tongues of one section into overlapping relation with the body of the other section as shown in Figures 8 and 9. However, to permit of more readily moving the sections laterally toward each other, their tongues 12 are previously bent slightly upward as shown in Figure 7 by passing the sections over a pair of balls 16 which contact with the tongues of the sections, to slightly deflect the same upwardly and thus separate their side edges. Also, after the sections are laterally moved toward each other, they are bent downwardly as shown in Figure 10, to slightly separate the side edges of the tongues, both steps being for the purpose of preventing any binding action between the tongues.

The next step in the operation of forming the hinge comprises the passing of the overlapping sections through the second pair of forming rolls 3 which bend the bodies 11 of the sections upwardly relative to the tongues 12. Since the body of one section engages the tongues of the other section during its upward bending movement, the tongues are

also bent upwardly so that the bodies and tongues have the relative positions as shown in Figure 11. The tongues are further bent relative to their respective bodies by passing the sections through the stationary die 14 shown in Figures 12 and 13, which has a U-shaped recess therein with substantially parallel vertical side walls and a round lower end. The width of the recess decreases toward its rear end so that in addition to bending the sections into substantially U-shape, the sections are moved laterally toward each other to bring the tongues of one section into more of an overlapping relation relative to the bending of the other section.

The wire 15 which forms the hinge pivot and around which the tongues 12 of the sections are bent, is continuously advanced into the machine and between the tongues after the sections have assumed a substantially U-shape. This wire is advanced by the pairs of forming rolls 4, 5, 6, 7 and 8 and as a consequence, is advanced at the same speed as the strip 1. As shown in Figure 14, the wire is fed between the tongues of the two sections and adjacent their bases.

After the engagement of the wire with the sections, the tongues of the sections are then fashioned around the wire and the first step in fashioning these tongues around the wire comprises the passing of the sections with the wire through the pair of idler forming rolls 16 as shown particularly in Figure 15, these rolls having portions for engaging the bodies 11 of the sections and swinging the same downwardly with respect to each other as well as moving the same laterally toward each other whereby the tongues of the sections are moved around the wire so that they cooperate to surround the same.

The next step in the fashioning of the tongues of the sections around the wire comprises the passing of the sections with the wire through the fourth pair of forming rolls 5 which swing the bodies of the sections downwardly into the same plane and bend the ends of the tongues around the wire, the partially completed hinge now having the cross sectional appearance as shown in Figure 16. After passing through the pair of forming rolls 5, the partially fashioned sections and the wire then pass through the fifth set of forming rolls 6 which incline the bodies of the sections upwardly and more completely bend the tongues of the sections, and particularly their bases, around the wire so that their ends more nearly engage their respective bodies. The sections and wire then pass through the sixth set of forming rolls 7 which again swing the bodies of the sections downwardly into the same plane and more completely bend the tongues of the sections

around the wire. Then the sections and the wire are passed through the last set of forming rolls 8 which again incline the bodies of the sections upwardly and complete the bending of the tongues around the wire. Figures 17, 18 and 19 show the three last-mentioned steps in the method of forming the hinge. After passing through the machine, the completed hinge has the appearance shown in Figure 20, but is of indeterminate length and can be cut to any length or lengths desired.

By rotating the bodies of the sections alternately upwardly and downwardly, the fashioning of the tongues around the wire and also the eliminating of the raw edges upon the sections is facilitated as well as the binding action of the tongues is prevented.

With the above method, it will be readily seen that a completed hinge is formed from a flat metallic strip during its advancement, this advancement being in the present instance continuous.

What I claim as my invention is:—

1. The method of forming a hinge which comprises the severing of a strip during its advancement into a plurality of sections, and the fashioning of the sections during the advancement of the strip into hinge members.

2. The method of forming a hinge which comprises the severing of a strip during its advancement into a plurality of sections having longitudinally spaced tongues, and the subsequent fashioning of the tongues during the advancement of the strip into barrels to form the sections into hinge members.

3. The method of forming a hinge which comprises the severing of a strip during its advancement into a plurality of sections, and the fashioning of the sections around a wire during the advancement of the strip and the wire.

4. The method of forming a hinge which comprises the severing of a strip during its advancement into a plurality of sections having longitudinally spaced tongues, and the subsequent fashioning of the tongues around a wire during the advancement of the strip and wire to form cooperating hinge members pivotally connected to each other.

5. The method of forming a hinge which comprises the continuous advancing of a strip, and the successive steps of severing the strip into sections, and fashioning and pivotally connecting the sections to form cooperating hinge members.

6. The method of forming a hinge which comprises advancing a strip and during the advancement of the strip forming cooperating hinge members from the strip and pivotally connecting the hinge members.

7. The method of forming a hinge which comprises the shearing of an advancing metallic strip into a plurality of sections, and

the subsequent fashioning of the sections during the advancement of the strip to form hinge members thereof.

8. The method of forming a hinge which comprises the shearing of a metallic strip into a plurality of sections, and the simultaneous advancing and fashioning of the sections into hinge members.

9. The method of forming a hinge which comprises the advancing of a wire in predetermined relation to an advancing section having longitudinally spaced tongues, and the fashioning of the tongues around the wire during the advancement of the wire and section.

10. The method of forming a hinge which comprises continuously advancing a strip, severing the strip into a pair of sections having alternate interengaging tongues, the lateral moving of the sections toward each other during advancement of the sections to bring the same into overlapping relation, and the fashioning of the tongues into hinge barrels during the advancement of the sections.

11. The method of forming a hinge which comprises the severing of a strip into a pair of sections having alternate interengaging tongues extending longitudinally thereof, the deflecting of the outer ends of the tongues of one section outwardly beyond the plane of the body of the other section, the lateral moving of the sections toward each other to bring the same into overlapping relation, and the subsequent fashioning of the tongues into hinge barrels.

12. The method of forming a hinge which comprises the advancing of a flat metallic strip, the severing of the strip into a pair of sections having laterally interengaging tongues extending longitudinally thereof, the crimping of the tongues to deflect the outer ends of the tongues of one section beyond the plane of the body of the other section, the lateral moving the sections toward each other to bring the tongues of one section into overlapping relation with the body of

the other section, the fashioning of the sections to bring their tongues into substantially parallel relation to their respective bodies, the advancing of a wire between the tongues of said sections and the subsequent fashioning of the tongues around the wire to form hinge barrels.

13. The method of forming a hinge which comprises the continuous advancement of a strip of indeterminate length, and the successive steps during the advancement of the strip, of severing the strip into sections, and subsequently fashioning the sections into hinge members.

14. The method of forming a hinge which comprises the continuous advancement of a flat metallic strip, the shearing of the strip into a pair of sections having alternate interengaging tongues extending longitudinally thereof, the continuous advancement of a wire into predetermined relation to the sections, and the subsequent fashioning of the tongues of the sections around the wire into hinge barrels during the continuous advancement of the strip and wire.

15. In the method of forming a hinge, the simultaneous advancing and fashioning of the interengaging tongues extending longitudinally of a pair of strips to form the tongues into hinge barrels.

16. In the method of forming a hinge, the advancing of a pair of sections having alternate interengaging tongues extending longitudinally thereof, and the pivotal connecting of the sections during their advancement.

17. In the method of forming a hinge, the continuous advancing of a pair of sections having alternate interengaging tongues extending longitudinally thereof, the advancing of a wire in predetermined relation to the tongues of the sections, and the subsequent fashioning of the tongues of the sections around the wire to form hinge barrels.

In testimony whereof I affix my signature.

H. G. KELLOGG.
